(57) **CLAIM**

The ornamental design for a kombucha brewing device, as shown and described.

DESCRIPTION

FIG. 1. is a perspective view of a kombucha brewing device, showing our new design;

FIG. 2. is a front view thereof;

FIG. 3. is a rear view thereof;

FIG. 4 is a right side view thereof;

FIG. 5 is a left side view thereof;

FIG. 6 is a top view thereof; and,

FIG. 7 is a bottom view thereof.

My device design is characterized by a rounded rectangular form with a vertical shaped window.

The broken lines, and the surface immediately inside the broken lines, form no part of the claimed design.
